UNITED STATES PATENT OFFICE

FRANCIS LEVITT IMPEY, OF NORTHFIELD, ENGLAND, ASSIGNOR TO MORLAND &
IMPEY LIMITED, OF BIRMINGHAM, ENGLAND

LOOSE-LEAF BINDER

Application filed November 11, 1930, Serial No. 494,939, and in Great Britain April 12, 1930.

This invention relates to loose leaf binders, and particularly binders in which the leaves are arranged in an overlapping or stepped formation, so that all of a number of 5 sheets are in part visible simultaneously, and in which the leaves are correlated by means of posts passing through holes in the leaves.

One example of a loose leaf binder to which the present invention is adapted is described 10 and illustrated in my Patent No. 1,841,894, dated January 19, 1932.

The principal object of the present invention is to provide an improved construction of the posts.

15 The invention comprises the combination of a plurality of hollow tapered posts each of which is flanged at one end, and a pair of strips (one of which may be a leaf supporting sheet) between which the flanged ends 20 of the posts are secured. Also the invention comprises the combination with some of the posts of compensating pieces as hereinafter described.

In the two accompanying sheets of 25 explanatory drawings:—

Figure 1 is a part section plan and Figure 2 a rear view of a loose leaf book provided with this invention.

Figure 3 is a longitudinal section and Figure 4 a transverse section of a portion of a leaf supporting sheet having attached thereto posts constructed in accordance with this invention. Figures 5 and 6 are respectively the rear elevation and the end elevation of a portion 35 of a supporting leaf provided with posts and strips as aforesaid and also with a spacing piece.

Figure 7 is a plan of one side and Figure 8 a plan of the other side of the portion of the 40 leaf supporting sheet shown in Figures 5 and 6.

In carrying the invention into effect as shown, each hollow post *a* is made from thin sheet metal or tubing, and is of tapered form, 45 allowing corresponding posts in an assembly of leaves to be nested together. Each post may be open at both ends, or as shown it may be open at one end and closed at the other. The base of each post is formed with an external flange *b*, and the posts in each row

are secured at the required distance apart by a pair of strips *c*, *d*, which grip the flanges between them, the posts being arranged to project through holes in one or both of the strips. One of the strips *c* may consist of a 55 narrow piece of thin metal, and the other *d* may consist of a sheet of thin cardboard or stiff paper on which the leaves are supported. The metal strip is secured to the other by tongue pieces *e* on the metal strip arranged to grip the supporting sheet; one row of 60 tongue pieces passes through holes *f* in the supporting sheet and are bent over the underside of the sheet, while the other row grips the rear edge of the sheet, as shown in Figures 7 and 8. In this construction I prefer to form tongue pieces *g* on the flange of each post, which tongue pieces can be pressed through the paper sheet *d* and bent over to 65 secure the post.

In one application of the invention a supporting sheet with posts attached as above described is used for supporting a number of leaves *h*, and different groups of leaves with intermediate supporting sheets can be 70 superimposed, the projecting parts of the posts in each group being caused to enter the hollow interiors of the corresponding posts in the adjacent group. The posts associated with each sheet *d* are arranged to project alternately at opposite sides of the sheet, and 75 preferably one set of posts is provided with more pointed outer ends than the other to facilitate entry into the hollow interiors of the posts having blunt ends. The differences 80 in the configuration of the posts is clearly 85 shown in, for example, Figures 3 to 6.

By this invention the posts required for the location of the leaves can be provided in a very simple and convenient manner.

When the posts are used for holding in proper relationship a group of overlapping sheets as aforesaid and as shown in Figure 2, the thickness of the group at its upper and lower edge is less than at the center as will be 90 seen at Figure 2, and to compensate for this inequality of thickness, so as to make the spacing between each pair of supporting sheets as uniform as possible, the supporting sheets *d* are sometimes embossed near their upper 95 100

and lower parts or are provided with separate compensating pieces. According to one part of my present invention I also provide compensation pieces *i* in combination with the ends of the strips *c* which carry the posts. These compensating pieces may take a variety of forms. In one convenient form as shown I attach to the rear edge of the underside of the supporting sheet at each end a short metal strip *i* of channel section the outer surface of which stands above the surface of the supporting sheet sufficiently to afford the required compensation. The edges of this compensating piece are secured by the tongue pieces *e* which clamp the metal retaining strip to the supporting sheet, and the compensating piece is perforated to allow a post or posts to project through it.

In the example illustrated groups of leaves as above described are secured between clamping bars *h* provided with posts *l* which pass through holes *m* in the members carrying the parts *a*.

Having thus described my invention what I claim as new and desire to secure by Letters Patent is:—

1. In loose leaf binders, the combination of a leaf-supporting sheet, a plurality of hollow tapered posts, a flange formed integrally with the larger end of each post, a perforated strip disposed along one edge of and adapted to co-operate with the supporting sheet for securing the posts, the flanged ends of the posts being interposed between said strip and said sheet, and tongue pieces formed integrally with each longitudinal edge of the strip, one row of tongue pieces being engaged with one edge of the supporting sheet and the other set being inserted through perforations and engaging the edges defining said perforations in the supporting sheet, for securing together the strip, the flanged posts and the supporting sheet, substantially as described.

2. In loose leaf binders, the combination of a leaf-supporting sheet, a plurality of hollow tapered posts, a flange formed integrally with the larger end of each post, tongue pieces on the post flange adapted to engage the supporting sheet, a perforated strip disposed along one edge of and adapted to co-operate with the supporting sheet for securing the posts, the flanged ends of the posts being interposed between said strip and said sheet, and tongue pieces formed integrally with each longitudinal edge of the strip, one row of tongue pieces being engaged with one edge of the supporting sheet and the other set being inserted through perforations and engaging the edges defining said perforations in the supporting sheet, for securing together the strip, the flanged posts and the supporting sheet, substantially as described.

3. In loose leaf binders, the combination

of a leaf-supporting sheet, a plurality of hollow tapered posts, a flange formed at the larger end of each post, a perforated strip disposed along one edge of and adapted to co-operate with the flanges on the posts for securing the posts to the supporting sheet, the flanged ends of the posts being interposed between said strip and said sheet, said posts being adapted to receive leaves arranged on the supporting sheet in stepped formation, and compensating pieces associated with the posts at the upper and lower edges of the supporting sheet, the depth of each compensating piece being approximately equal to the thickness of the group of leaves placed on the supporting sheet, substantially as described.

In testimony whereof I have signed my name to this specification.
